UNITED STATES PATENT OFFICE.

IRA C. MANAHAN, OF GOSHEN, INDIANA.

GLIDING SETTEE.

No. 873,381.

Specification of Letters Patent.

Patented Dec. 10, 1907.

Application filed August 5, 1907. Serial No. 387,156.

To all whom it may concern:

Be it known that I, IRA C. MANAHAN, a citizen of the United States, residing at Goshen, in the county of Elkhart and State of Indiana, have invented certain new and useful Improvements in Gliding Settees; and I do hereby declare the following to be a full, clear, and exact description of the invention, such as will enable others skilled in the art to 5 which it appertains to make and use same, reference being had to the accompanying drawings, and to the letters and figures of reference marked thereon, which form a part of this specification.

15 This invention relates to new and useful improvements in gliding settees and the object of the invention is to produce a simple and efficient apparatus of this nature, which may be given a reciprocating movement by 20 persons sitting on the same, the movement being effected by the limbs of the operator who, while sitting upon the seat, rests his or her feet upon a movable platform.

25 The invention comprises various details of construction and combinations and arrangements of parts which will be hereinafter fully described and then specifically defined in the appended claims.

30 I illustrate my invention in the accompanying drawings, in which:—

Figure 1 is a perspective view of the settee. Fig. 2 is an end view. Fig. 3 is a sectional view on line 3—3 of Fig. 2, showing parts in elevation. Fig. 4 is an enlarged perspective 35 view of one of the axles and rocking members mounted thereon. Fig. 5 is a sectional view on line 5—5 of Fig. 3. Fig. 6 is a detailed sectional view through one of the rocking members. Fig. 7 is a detailed perspective 40 view showing the caster carrying strip which is rotatable. Fig. 8 is a perspective view of the apparatus showing the backs of the seats turned down, whereby the apparatus may be utilized as a bed, and Fig. 9 is a 45 detail sectional view.

Reference now being had to the details of the drawings by letter, A designates a frame of the apparatus upon which the settee is supported, and B—B designate two strips, 50 the ends of which are pivotally mounted in suitable bearings near the ends of the frame, said strips each carrying a swiveled caster wheel B'. Each of said cross pieces A² of said frame, it will be noted is provided with a 55 shoulder A³ upon the outer edge thereof and

B² designates a laterally projecting wing upon each piece B which is adapted, when the casters are turned down, to rest upon said projection A³, as shown clearly in the detail view of the caster carrying strip.

60 In order to hold the strips B so that the weight of the apparatus will rest upon the casters, a button B⁴ is pivotally mounted upon the frame, one end of which is adapted to swing over the strip B, as shown clearly in the drawings. By this mechanism, it will be observed that the casters may be thrown in such a position as to support the weight of the settee or may be thrown up into such a position that the frame will rest stationary.

65 C—C designate bracket arms, made preferably of any suitable metal, each of which is fastened to the frame and near the upper end of each of said bracket arms is a bearing aperture C' circular in outline and a slot C² leads 70 through the top of each bracket member into said bearing openings. It will be noted that there are two of said bracket arms near each end of the frame and arranged opposite each other.

75 D—D designate axles, made preferably of steel, and of rectangular shape in cross section with their ends cut away as at D' adapted to be inserted through the slots in the ends of the bracket arms, and rest in the circular bearing openings formed therein. It will be noted that the weight of the settee 80 will come upon said axle and, by the provision of the peculiar shape of the axles, the friction intermediate the ends of the axles 85 and the bearings will be reduced to minimum.

85 E—E designate two arms which are fastened to or integral with each axle, said arms being disposed substantially at right angles 90 to each other near the ends of the axles and fastened to the outer angled ends of said arms is a rocker F made on the arc of a circle of substantially twenty inches in diameter. Said rocker is provided preferably with a 95 solid rubber cushion F', which may be secured in place in any suitable manner, preferably by passing wires longitudinally through the same and fastening them in place by means of nuts. Rods F² are fastened to said arms in order to securely brace 100 the same.

105 G—G designate two seats having hinged backs G' which may be thrown down to horizontal positions, whereby the device may be 110

converted into a bed, if desired, and suitable arms G² are provided for each seat.

G³ designates segment members which are fastened to said arms and provided with apertures adapted to receive pins carried by the hinged back and adapted to engage one or another of the apertures in said segment members, whereby the angle at which it may be desired to have the backs positioned 5 may be adjusted. In the drawings, the backs and seats are shown as made of slats, the usual construction in settees. In order to further reinforce the seat, the rods G⁴ are passed through the cross-pieces of the seats. 10 15 H designates coiled springs which are fastened at their upper ends to said rods G⁴ and their lower ends are secured to the rods F² which connect said arms.

Upon reference to the under side of each 20 seat, it will be noted that the cross-pieces G⁵ each is provided with a longitudinal groove adapted to receive one of the rockers, said cross-pieces being substantially the length of a rocker.

25 K designates a platform having the beams K' which carry the wheels L in suitable brackets and are fastened to the under edges thereof, said wheels being adapted to travel back and forth upon the upper surface of the 30 longitudinal side strips of the platform. It will be noted that the projecting strips K' are positioned adjacent to the outer faces of said bracket arms which guide the platform as it moves back and forth.

35 N designate bars which are pivotally fastened at their inner ends to said platform and which bar N has a free hooked end N' designed to engage one or the other of the apertures in the laterally projecting arms O 40 upon the axles, whereby the platform and seats may be caused to move back and forth in unison, although the speeds at which the platform and seats move vary owing to the fact that the bars N have pivotal connection with the projections upon the axles 45 at a location intermediate the bearing surfaces of the rockers and the axis of the axles.

From the foregoing, it will be noted that, 50 by the provision of the apparatus shown and described, a simple and efficient mechanism is afforded whereby a settee may be given a reciprocating movement by the motion of the body and limbs of the operator sitting upon the seats and placing their feet upon 55 the platform, the motion of the body to and fro or of the legs bearing upon the platform

being sufficient to cause the axles to rock and give the desired movement.

When it is desired to utilize the apparatus 60 as a bed, the two backs may be turned down to horizontal positions, one overlapping the other as shown, thereby forming a comfortable bed upon which a mattress may be placed between the arms of the settee.

What I claim to be new is:—

1. A settee comprising a frame, axle bearings mounted thereon, rocking axles mounted in said bearings, rockers fixed to said axles, seats supported upon said rockers, a platform, wheels carried thereby and adapted to rest upon said frame, rods pivotally connected to said platform and having hooked ends adapted to be attached to projections upon said axles, as set forth. 70

2. A settee comprising a frame, axle bearings mounted thereon, rocking axles mounted in said bearings, arms projecting from said axle, rockers fixed to the ends of said arms, seats supported upon said rockers, rods connecting said arms, springs connected to said 80 rods and also to said seats, a movable platform, and pivotal connection between the latter and said axles, as set forth.

3. A settee comprising a frame, axle bearings mounted thereon, angular outline axles 85 resting upon an edge in the bearing openings in said bracket arm, arms fastened to said axles, rockers fastened to said arms, seats having grooved ways in the under surfaces thereof and adapted to receive said rockers, 90 rods connecting said arms, coiled springs fastened to said rods and to said seat, a movable platform, and pivotal rod connections between the same and said axles, as set forth.

4. A settee comprising a frame, axle bearings mounted thereon, rocking axles mounted in said bearings, rockers fixed to said axles, seats supported upon said rockers, a movable platform, connections between the same and said axles, axially movable strips 100 mounted upon said frame, casters carried by said strips, said frame having a shouldered portion adapted to receive a projecting part of said axially movable strip, and a button adapted to hold said projecting part upon 105 the shoulder, as set forth.

In testimony whereof I hereunto affix my signature in the presence of two witnesses.

IRA C. MANAHAN.
